UNITED STATES PATENT OFFICE.

STEPHEN J. COX, OF NEW YORK, N. Y., ASSIGNOR TO GEORGE W. STEWART,
OF ATLANTA, GEORGIA.

DESIGN FOR ORNAMENTING BOTTLES.

SPECIFICATION forming part of Design No. 14,154, dated August 7, 1883.

Application filed June 26, 1883. Term of patent 14 years.

To all whom it may concern:

Be it known that I, STEPHEN J. COX, a citizen of the United States, residing in the city, county, and State of New York, have invented and produced a new and original Design for Ornamenting Bottles, of which the following is a specification, reference being had to the accompanying drawing, forming part thereof.

The drawing represents a front view of a bottle with my design applied upon its side.

My design comprises the crescent-shaped moon or figure A, the feathered arrow B, and the stars C, as represented. The arrow appears as having pierced the crescent on its concave side, its barb being exposed on one side and its stem or tail on the other side of the crescent figure. The stars appear as arranged about the feathered end of the arrow.

In the use of my design upon bottles it is contemplated to have certain descriptive words above, below, and around the design, accordingly as circumstances may require; but these words form no part of my design, as the leading feature of my design is the ornament comprising the crescent moon and the arrow with stars about its stem or tail, arranged essentially as represented.

What I claim is—

The design, as shown and described, for ornamenting bottles.

STEPHEN J. COX.
